[57] CLAIM

The ornamental design for a roof tile, as shown.

DESCRIPTION

FIG. 1 is a perspective view of the roof tile of the present invention;

FIG. 2 is a front elevational view of the invention of FIG. 1;

FIG. 3 is a top plan view of the invention of FIG. 1;
FIG. 4 is a bottom plan view of the invention of FIG. 1;
FIG. 5 is a back elevational view of the invention of FIG. 1; and

FIG. 6 is a side elevational view of the invention of FIG. 1.

FIG. 1.

FIG. 2.

FIG. 3.

FIG. 4.

FIG. 5.

FIG. 6.
